CLAIM

The ornamental design for a basket, as shown and described.

DESCRIPTION

FIG. 1 is a front perspective view of a basket showing my new design;
FIG. 2 is a front view thereof;
FIG. 3 is a back view thereof;
FIG. 4 is a right side view thereof;
FIG. 5 is a left side view thereof;
FIG. 6 is a top view thereof;
FIG. 7 is a bottom view thereof;
FIG. 8 is the embodiment of FIG. 1 showing a horizontal break indicating varying vertical heights;
FIG. 9 is a front view thereof;
FIG. 10 is a back view thereof;
FIG. 11 is a right side view thereof;
FIG. 12 is a left side view thereof;
FIG. 13 is a top view thereof;
FIG. 14 is a bottom view thereof;
FIG. 15 is a front perspective view of an alternative embodiment of the basket showing my new design;
FIG. 16 is a front view thereof;
FIG. 17 is a back view thereof;
FIG. 18 is a right side view thereof;
FIG. 19 is a left side view thereof;
FIG. 20 is a top view thereof;
FIG. 21 is a bottom view thereof;
FIG. 22 is a front perspective view of the basket of FIG. 15 showing a horizontal break indicating varying vertical heights;
FIG. 23 is a front view thereof;
FIG. 24 is a back view thereof;
FIG. 25 is a right side view thereof;
FIG. 26 is a left side view thereof;
FIG. 27 is a top view thereof; and,
FIG. 28 is a bottom view thereof.

The broken lines illustrate portions of the basket and form no part of the claimed design.
